COMBINED HEAT BAFFLE AND FILTER ATTACHMENT

Ted M. Parker, Independence, Mo.

Application September 16, 1955, Serial No. 534,692

1 Claim. (Cl. 183—51)

The present invention relates to combined heat baffles and filter attachments for baseboard and wall attached heat registers, and more particularly for heat registers of the type used with forced air heating systems.

In forced air heating systems of the type employing registers along the baseboard or in the wall of a room, the flow of air through the register has carried a sufficient amount of dirt, not eliminated by the furnace filter, to smudge the wall surface above the register after prolonged periods of heating. Efforts have been made to produce furnace filters which will completely eliminate the problem. However, it has been found that such filters cannot be produced at a cost which would make them economical to install. Hence, the smudging of the wall above the register has been generally accepted as a necessary evil of the forced air register heating system, therefore—

The primary object of the invention is to provide a combined heat baffle and filter attachment for hot air registers which will simultaneously deflect the heated air outwardly away from the wall lying just above the register, and filter the layer of air lying closest to the baffle.

Another object of the invention is to provide an air filtering baffle in which the filter is arranged in such a manner that it can be readily removed and replaced upon becoming saturated with dirt.

A further object of the invention is to provide a heat baffle structure for attachment to an air register which will produce the desired effect of eliminating the smudging of the wall above the register and at the same time present a neat appearance which will not be objectionable to the eye of the user.

A still further object of the invention is to provide a combined heat baffling and filtering attachment for hot air registers which will be inexpensive to manufacture, easy to maintain and simple to install.

Other objects and advantages will become apparent in the following specification when considered in the light of the attached drawings, in which:

Figure 1 is a perspective view of the invention, shown attached to a conventional air register structure;

Figure 2 is an enlarged vertical cross section taken along the line 2—2 of Figure 1, looking in the direction of the arrows;

Figure 3 is a fragmentary front elevation of the attachment showing the relationship of the filter thereto, and

Figure 4 is a fragmentary detail view of the filter element, showing the stitching thereof.

Referring now to the drawings in detail wherein like reference numerals indicate like parts throughout the several figures, the reference numeral 10 indicates generally a heat register of the type normally associated with a forced air heating system. The heat register 10 is of a conventional nature and is shown merely to illustrate the manner in which the invention is attached thereto, and can have any conventional form.

The heat register 10, as disclosed herein, rests on the floor 11 and against a wall 12. A baseboard 13 en-

gages the sides 14 of the register 10 to complete the finish of the room. The register 10 is provided with louvers 15 on the forward face 16 thereof, which communicate with the internal portions 17 of the register 10. 5 Heat ducts (not shown) are connected to communicate with the internal portions 17 of the register 10.

An arcuate baffle 18 has a downwardly extending flange 19 projecting therefrom with the flange 19 extending in front of the top face of the register 10 and is 10 secured thereto by means of fastening elements 20. The arcuate portion 18 has a generally semi-cylindrical cross section with the concave portion 21 thereof facing outwardly toward the interior of the room. The baffle 18 has one end edge 22 positioned adjacent the end 14 of the register 10, and the other end edge 23 positioned adjacent the end wall 13 of the register 10 so that the baffle 18 extends completely across the top of the register 10.

A filter 24 made of a wire screen tubing 25, formed 20 around the filtering material such as glass wool 26, is secured together by means of wire stitching 27 along one edge. The filter 24 extends throughout the length of the baffle 18 and is positioned adjacent the top outer edge 28 thereof. Filter 24 underlies the outer edge 25 28 of the baffle 18 and is secured thereto by means of metal screws 29, or other suitable fastening devices.

In the use and operation of the invention, the baffle structure 18, with the filter 24 attached thereto, is secured to the upper face of the register 10 by means of 30 the fastening elements 20. In this position heated air flowing upwardly from the louvers 15 rises and, instead of contacting the wall 12, is deflected outwardly by the concave curve 21 of the baffle 18. The layer of air 35 closest to the baffle 18 is filtered through the filter 24, removing the dirt therefrom and producing a cushion of clean air extending upwardly between the air not filtered through the filter 24 and the wall 12. This, as it can be readily seen, will prevent the smudging of the wall 12 due to the unfiltered air coming in contact therewith.

40 It will be understood that this baffle and filter will be made to fit any and all sizes of heaters, floor registers, where heat flows or is forced; floor furnaces, wall furnaces, or hot water heaters.

Having thus described the preferred embodiment of 45 the invention, it should be understood that numerous modifications and design changes to attach the device to all types and styles of heat registers and/or radiators may be resorted to without departing from the scope of the appended claim.

50 What is claimed is:

A combined air deflecting heat baffle and filter attachment for hot air registers of the type including a generally rectangular body having the rear thereof engaged against a building wall and the front thereof spaced outwardly 55 therefrom comprising, an imperforate semi-cylindrical body portion having a forwardly facing concave form, a flange integrally depending from said semi-cylindrical body portion, means detachably securing said flange to the front upper edge of said register, a wire fabric tube, 60 filter material in said tube, and means securing said tube horizontally to the upper edge portion of the concave side of said semi-cylindrical body portion for filtering air.
